HYDRAULIC DEVICE

Max J. Clark, Pontiac, Mich.

Application May 4, 1936, Serial No. 77,738

17 Claims. (Cl. 60—52)

This invention relates to hydraulic devices and more particularly to such hydraulic devices as may be adapted for use in connection with various types of machine tools and other contrivances for effecting hydraulic feeds and controls in the operation thereof.

In connection with the devices of the above character, it is desirable to have pumps which, while operating substantially at constant speeds, usually from mechanical drives, can quickly vary their rate of discharge in order to produce a rapid advance of the actuated member through a considerable distance into a certain position, a movement thereof through a desired distance at a slow predetermined rate, and a rapid return of said actuated member to its original position. For instance, in connection with a drill press, it is desirable to have an oil pump capable of varying its discharge in such a way as to effect, when desired, a rapid movement of the drill toward the work, a slow feeding of said drill into the work to a desired depth, and a rapid return thereof to its starting position. In connection with such devices it has been found highly undesirable to have a pump the rate of intake of which is constant, while the control of its rate of discharge is accomplished through by-passing the surplus amount of fluid into the escape conduit, since in such case the pump will always operate at its full capacity consuming maximum power. Moreover, throttling the liquid fluid, that is, forcing the same through a restricted orifice under a high pressure, produces excessive heating of the fluid, making it impossible to operate such pumps on a limited amount of fluid and rendering them inapplicable to uses with machines in which only a limited space may be allowed for storing the fluid.

It is apparent, therefore, that a pump in which the rate of discharge equals or substantially equals the rate of intake will possess many advantages in connection with the above uses, since it will effect a large economy in the power consumed, because such a pump will not operate at its maximum capacity at all times. As a consequence the life of the pump will be prolonged, permitting operation of comparatively large machines on a very limited amount of oil and preventing heating of the oil or of other fluid used. Accordingly, it is an important object of the present invention to provide a hydraulic device which may be adapted for use with machine tools and other contrivances for effecting hydraulic feeds and controls, and which includes a positive acting pump in which the rate of discharge is

controlled by the change of volumetric displacement of the pump, and particularly in which said change of volumetric displacement is effected automatically by novel means responsive to pressures resulting from the operation of the pump, whereby such rate of discharge as is necessary for producing a desired type of movement of the hydraulically actuated member is automatically effected.

Another object of the present invention is to provide a hydraulic pump adapted to pump the fluid only in such quantities as are necessary for effecting the desired movements of the hydraulically actuated member, thus effecting considerable economy in power consumption, and permitting operation of large machines on a very limited amount of fluid without the danger of excessive heating of said fluid.

A further object of the invention is to provide a rotary oil pump for use in hydraulic feed and control devices, in which the amount of eccentricity of the rotor, determining the discharge of the pump, is automatically controlled by the pressures resulting from the operation of the pump and is varied so as to effect changes in the rate of discharge from the "no-discharge" to the discharge corresponding to the maximum capacity of the pump.

A still further object of the invention is to provide a novel device for effecting hydraulic feeds and controls, having a metering device adapted to be operated by the pump, which metering device will operate to relieve the back pressure acting upon the hydraulically actuated piston, determining thereby the rate of feeding movement of said piston and the member connected thereto.

A still further object of the invention is to provide a metering device of the character mentioned, which has regulating means whereby the rate of its operation is regulated and changed as desired.

A still further object of the invention is to provide a device for effecting hydraulic feeds and controls, having a hydraulically balanced, manually operated control valve, the shifting of which into a respective position for rapid movement of the operating piston directs the discharging fluid into the operating cylinder and at a proper side of the piston arranged therein, connecting at the same time the space on the opposite side of the piston with a free escape opening and at the same time cutting communication of the displacement-decreasing cylinder with said opposite side.

It is a still further object of the invention to provide a control valve of the above character which operates, when set for feed movement of the operating piston, to establish a connection of the displacement-controlling cylinder with the back pressure side of the operating cylinder.

A still further object of the invention is to provide a rotary pump having a rotor-encircling ring of constant, built-in eccentricity, the volumetric displacement of said pump being varied from zero to the full capacity displacement by changing the position of said rotor encircling ring with respect to the intake and discharge vanes of the pump.

A still further object of the invention is to provide a pump of the character mentioned in the preceding paragraph, having means responsive to pressures resulting from the operation of the pump for changing the position of said rotor-encircling ring in accordance with said pressures.

Still another object of the invention is to provide a hydraulic pump having a concentric rotor-encircling ring and means responsive to the pressures resulting from the operation of said pump for moving said concentric rotor-encircling ring into a position of greater eccentricity when said means are exposed to said pressures.

Other objects and advantages of the present invention will appear more fully hereinafter from a consideration of the following description and appended claims, reference being had to the accompanying drawings wherein two embodiments of the invention are illustrated.

In the drawings, wherein like reference characters refer to like parts throughout the several views,

Fig. 1 is a view illustrating diagrammatically the hydraulic circuit embodying the present invention, and showing the pump in transverse vertical section, the control valve and the operating cylinder being shown in longitudinal cross-section.

Fig. 2 is a longitudinal sectional view of the pump taken on the line 2-2 of Fig. 1.

Fig. 3 is in part a view similar to that of Fig. 1, showing the control valve and the stop valve in positions for idling operation of the pump.

Fig. 4 illustrates the position of the control valve for causing a rapid advance movement of the hydraulically actuated operating piston.

Fig. 5 illustrates the position of the control valve for causing a rapid return of the hydraulically actuated operating piston into its starting position.

Fig. 6 is a view similar to that of Fig. 1 illustrating a modified form of my invention.

Fig. 7 is a longitudinal sectional view of the pump of modified construction, section being taken on the line 7-7 of Fig. 6.

Fig. 8 illustrates the position of the control valve, stop valve, and the pump rotor, for idling operation of the pump of Fig. 6.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

In the drawings there is illustrated, by way of

example, a hydraulic device embodying my invention which comprises a positive pump of rotary type, designated generally by the numeral 20, a manually or otherwise operated control valve, designated generally by the numeral 40, and a hydraulically actuated member represented by a piston 61 arranged in a suitable operating cylinder 60. A piston rod 62 is connected to the member, the movement of which it is desired to control, such as a drill, a cutting tool of whatever kind, a control lever, and the like. Said pump, control valve, and the operating cylinder are interconnected by means of a number of suitable conduits. The control valve 40 is provided with a number of escape outlets leading into an oil storage tank (not shown). The control valve 40 may be manually operated with the aid of a suitable lever. The pump 20 is provided with means for changing its volumetric displacement, which means are automatically regulated by the hydraulic pressure resulting in the circuit because of the operation of the pump when the control valve is set in respective operative positions. When the control valve is set for rapid advance of the hydraulically actuated piston, the pump operates at its largest displacement and, consequently, at its full capacity and is pumping oil into the operating cylinder 60 and to the desired side of said piston (pressure side), while the oil from the operating cylinder on the opposite side of the piston (back-pressure side) is allowed by the control valve to escape freely into the storage tank. For effecting a rapid return movement of the operating piston, the control valve is put in such a position that the oil is pumped into the back-pressure space of the operating cylinder, while the oil from the pressure side of the cylinder is allowed to escape freely into the oil storage tank. For effecting a slow movement of the actuated member, that is to say, the feed movement thereof, the control valve is put in such a position that while the oil is pumped into the pressure space of the operating cylinder, the oil from the space on the back-pressure side of the piston is prevented from escaping, thus building up back-pressure resisting the advance movement of the operating piston 61. In this condition, the only escape for the oil contained in the back-pressure space of the cylinder is through a special metering device, indicated generally in the drawings by the numeral 70, which device meters or measures off the oil at a predetermined rate, thus relieving the back-pressure on the piston 61 and allowing its advance movement of a predetermined rate. In this condition, the increased back-pressure in the cylinder 60 is allowed by the control valve 40 to operate upon special means which decrease the displacement of the pump substantially in inverse proportion to said back-pressure. Thus, in this condition the pump is operating at its partial capacity and is pumping only a very limited quantity of oil.

In the present embodiment the volumetric displacement of the pump is varied by affecting the eccentricity of the rotor-encircling ring of the rotary pump. In the preferred structure the eccentricity of the rotor-encircling ring is constant, and the control of displacement is effected by changing the position of the line of eccentricity of said ring with respect to the concentric rotor of the pump. In the modified structure the control of the pump displacement is effected by changing the amount of eccentricity between the fixed axis of the concentric rotor and the axis of the bodily movable rotor-encircling ring. It is

an important feature of my invention that control of the position of eccentricity in the preferred structure, as well as the control of the amount of eccentricity in the modified structure, is effected automatically with the aid of means responsive to the pressures resulting from operation of the pump. It is to be expressly understood that I do not desire to limit myself either to controlling pump displacement by affecting eccentricity of the rotary pump, or to the use of rotary pumps only, since use of other types of pumps requiring other methods of displacement control is within the purview of my invention.

Referring more particularly to Figs. 1 to 5, wherein the present preferred embodiment of my invention is illustrated, the pump 20 comprises a pump body 21 which supports a rotor shaft 25 and is bored concentrically therewith. Within said pump body 21 there is arranged a rotor-encircling ring 22 fitting by its turned cylindrical surface 23 into the concentric bore of said pump body 21. Said concentric surface of the ring 22 is milled or cut to form a gear portion 23a. The inner surface 24 of said ring 22 is bored eccentrically with respect to its outer surface 23 and, consequently, to the center line of the rotor shaft 25. The rotor shaft 25 carries a concentrically mounted rotor 26. The body of the rotor 26 is provided with a plurality of longitudinal radial slots, such as shown at 27, with slideable blades or paddles, such as shown at 28. The rotor 26 revolves between plates 29 and 30 arranged within the pump body. The plate 29 is provided with two arcuated slots 31 and 32, the slot 31 communicating with the intake conduit 11, and the slot 32 communicating with the discharge conduit 12 leading to the control valve 40.

Suitably affixed to or formed integrally with the pump body 21 is a displacement-controlling cylinder 34 which has a piston 35 operatively arranged therein. The piston 35 has a rack 36 attached to it, which rack engages the gear portion 23a of the rotor-encircling ring 22. The closed end 37 of the cylinder 34 houses a suitable helical spring 38 bearing against the end of the rack 36 and tending to keep the piston 35 in its fully extended position, and consequently acting in opposition to piston 35. The cylinder 34 communicates with the control valve 40 through a conduit 15.

In the present embodiment the gear portion 23a is formed on the outside surface of the rotor-encircling ring 22. However, I do not desire to limit myself to such construction, since such gear may be formed at any portion of said ring where its engagement with the rack is practical.

The rotor shaft 25 is provided with a suitable drive, such as a gear 33. Rotation of the shaft 25 and the rotor 26 at a speed above a certain minimum operates to push the blades or paddles 28 outwardly. Sliding outwardly in the radial slots 27 said blades engage the eccentrically bored surface 24 of the rotor-encircling ring 22. The pockets which are thus formed by the blades 28 change their volumetric capacity as they are moving along the arcuated slots 31 and 32. Considering the clock-wise direction of rotation of the rotor 26, it will be appreciated from an examination of Fig. 1 that as a respective pocket reaches the slot 31, it begins to increase its volumetric displacement, and a partial vacuum is, therefore, created therein. Since the slot 31 communicates with the intake pipe 11, the pockets will draw in the oil as they move along the slot 31 in the clock-wise direction. At the moment when a re-

spective pocket loses its communication with the slot 31 and, consequently, with the intake pipe 11, it is in a condition of its maximum displacement for the conditions of that particular revolution and, consequently, it holds the maximum quantity of oil which it is capable of holding under those conditions. As the pocket continues to move in the clock-wise direction, its volumetric displacement begins to decrease and the oil which it contains is gradually forced out into the slot 32 and therethrough into the discharge conduit 12. The distance between the extremities of the slots 31 and 32 is made greater than the distance between two adjacent blades, in order to prevent short circuiting of said slots by one pocket.

For producing the greatest aggregated volumetric displacement of the pump 20, the ring 22 is set in such a position that the line of eccentricity a—a of said ring passes through the points intermediate the extremities of the slots 31 and 32. Such a position of this ring 22 is illustrated in the Fig. 1. If the ring 22 is rotated in a clock-wise direction within the pump body 21 through an angle of 90°, and is thus brought into the position shown in Fig. 3, the line of eccentricity of the ring 22 a—a will assume the position in which it is passing through the middle points of the slots 31 and 32. It will be noticed that in this position of the pump ring, as the pockets move in the clock-wise direction, their displacement will be decreasing up to the middle point of the slot 31, and increasing in corresponding proportion after passing said point; and correspondingly, said displacement will be increasing up to the middle point of the slot 32 and decreasing in the same proportion after passing the same. Therefore, although there is a certain amount of flow of the fluid in the slots 31 and 32, nothing is being pumped from the conduit 11 or into the conduit 12. The above position is the position for the "no-discharge" operation of the pump, while the position shown in Fig. 1 indicates the setting of the pump 20 for operation at its maximum capacity. Any intermediate position of said line of eccentricity a—a will effect a displacement of the pump, which is below its maximum, and will cause the pump to operate at some intermediate capacity.

The control valve 40 comprises a valve body 41 provided with a cylindrical bore 42 adapted to receive a slideable member 50. At its ends, the valve body 41 is provided with covers 43 and 44. A conduit 16 provided with a manually operated valve 39 passes through the cover 43 and connects the valve space adjacent to the cover 43 with the discharge conduit 12. The slideable member 50 has recesses 51, 51a, 52, 53 and 54 cut in its body, as shown in the drawings. The extended end 55 of the member 50 is provided, in the present instance, with means whereby manual operation of the valve 40 is made convenient. Said means in the present embodiment of the invention are exemplified in the form of a rack portion 56 engaging the gear portion 57 of the lever 58. By moving said lever 58, the slideable member 50 may be set into any desired position within the bore 42 of the valve body 41.

The numerals 45, 46 and 15a indicate escape openings through which the oil may escape into the storage tank. Conduits 13 and 14 connect the control valve 40 with the cylinder 60 leading, respectively, to the advance or pressure space 63 and to the back pressure space 64 of said cylinder 60. Conduit 14 has two parts 14a and 14b leading into the bore 42. When in position of

closest proximity to the conduit 13 the piston 61 is in its starting position. Pumping the oil through the conduit 13 into the space 63 causes the piston 61 to move toward the conduit 14, causing at the same time the rod 62 and other hydraulically actuated members to advance toward the work. When the piston 61 is at the end of its stroke near the conduit 14, the rod 62 is in its fully extended position. When the oil is pumped into the cylinder 60 through the conduit 14, the piston 61 returns to its starting position.

The valve 39 comprises a suitable valve body in which there is slidably fitted a recessed piston 39a. Conduit 16 effects a constant communication of the end space of the governor valve 40 with the space formed by the recess in said piston 39a, while the waste port 16a is provided for the purpose of releasing the oil which may be entrapped in said end space, thus relieving the pressure in said space and permitting free movements of the slidable member 50 into any desired position. The piston 39a may be operated either independently, or may be operatively connected with the lever 58 in such way that when said lever 58 is in the position shown in Figs. 3 and 8, it moves the piston 39a into the position shown in said figures. Such an arrangement may be easily effected by disposing the valve 39 parallel to the valve 40 and connecting the piston 39a to a suitable gear portion mounted on the shaft of the lever 58.

The back-pressure space 64 is connected with the aid of conduits 17, 17 to the metering device 70. Said metering device is arranged at the shaft 25 of the pump 20, as shown in Fig. 2. Fig. 1 shows the device in a diagrammatic way in a position away from the pump, in order to illustrate the nature of the hydraulic cycle more clearly. The metering device 70 comprises a casing 71 enclosing the articulated end of the shaft 25 and having passageways 72, 72 and 73, 73 provided in its body. The end of the shaft 25 is provided with a concentric hole 25a and a transverse slot 75. An end piece 76 of the same diameter as that of the shaft 25, provided with a cylindrical portion adapted to engage the hole 25a and a milled portion adapted to engage the slot 75, is held in the end of the shaft 25. Moving the piece 76 out of said end will form two pockets 74, 74 between its body and the body of the shaft 25, the size of said pockets depending upon the position of the piece 76. In operative position, the end piece 76 is held between the spring 78 and a regulating screw 79. By adjusting the screw 79, the size of the pockets 74, 74 may be changed and their capacity varied from zero up to a certain predetermined limit. The passageways 73, 73 lead to free escape openings, while the passageways 72, 72 are connected with the conduits 17, 17, and through the conduit 14 with the back-pressure space 64 of the cylinder 60. The pockets formed by the end piece 76 as they revolve through each 90° angle register alternatively with the passageways 72, 72, hydraulically connected with the back-pressure side of the cylinder 60, and with the passageways 73, 73 leading to free escape openings as mentioned.

From the foregoing it will be appreciated that if oil is forced under high pressure into the conduits 17, 17 the pockets 74 will be filled each time they register with the passageways 72, 72. If the shaft 25 is rotating at a high speed, 1000 revolutions per minute for example, the oil contained in said pockets will be thrown out by the centrifugal force developed because of the rota-

tion of the pockets 74, 74. Thus, the metering device 78 will operate to "meter off" the oil at a certain predetermined rate depending upon the rotative speed of the shaft 25 and the adjusted capacity of the pockets. By adjusting the 5 regulating screw 79 and changing the size of the pockets, the rate of discharge through the metering device 78 may be varied within predetermined limits in any desired degree.

In operation of my novel device, when it is 10 desired to effect a rapid advance of the piston 61, the control valve 40 is set with the aid of the lever 58 as shown in Fig. 4. In this condition, the pump 20 will pump the oil through the conduit 12, recess 53 and conduit 13 into the pressure space 63 of the cylinder 60. The oil from the back-pressure space 64 will be allowed to escape through the conduit 14, recess 52, and escape opening 45 into the storage tank. With the spring 38 holding the piston 35 in its fully extended position, the pump 20 will operate at its full capacity and under a very slight pressure, effecting a rapid advance movement of the piston 61 and the rod 62.

If it is desired to change the rapid advance 25 movement of the rod 62 into a slow feeding movement, the member 50 of the control valve 40 is shifted with the aid of the lever 58 into the position illustrated in Fig. 1. In this condition, the free escape opening 45 will be cut off from 30 the conduit 14, and the oil contained in the back-pressure space 64 will not be permitted to escape. This will immediately deter the rapid advance movement of the piston 62. Since in this condition the space 64 is communicating 35 through conduit 14, port 14b, recess 51, and conduit 15 with the cylinder 34, back-pressure built up in the space 64 will be transmitted into the cylinder 34. Piston 35 will be moved against the compression of the spring 38, and acting through 40 the rack 36, it will begin moving the ring 22 into the position shown in Fig. 3. Now the oil from the space 64 will be metered off by the metering device 70 in accordance with the adjustment thereof, and will permit slow feeding movement 45 of the piston 61 and of the piston rod 62. In this condition, the pump will have a rate of discharge just sufficient to maintain this position. If it becomes necessary to return the piston 61 into its starting position, the same may be done rapidly 50 by moving the lever 58 so as to set the sliding member 50 into the position shown in Fig. 5. In this condition, the oil will be pumped through the discharge conduit 12, recess 53, and conduit 14 into the space 64, moving the piston 61 toward 55 its starting position, the oil from the space 63 being permitted to escape through the conduit 13, recess 54, and opening 46 into the storage tank.

In order to set the pump for idling operation, 60 the valves 39 and 40 are set in the positions shown in Fig. 3. In this condition, no oil will be pumped into or allowed to escape from the cylinder 60, and this will stop any movement of the piston 61. At the same time, the entire discharge of the pump 20 will be directed through the conduit 16, valve bore 42 and conduit 15 into the cylinder 34. With the piston 35 moved all the way into the cylinder the pump will be set for "no-discharge" operation. It should be 70 noted that Fig. 3 shows the position of the piston 35 after said action has taken place, and the piston 35 is moved from its retracted position to the position shown. During the first few moments following moving of the member 50 to 75

the position shown in Fig. 3, the piston 35 is in its retracted position shown in Fig. 1. However, all volume and pressure of the entire discharge of the pump being directed through the conduits 5 12, 16 and 15 into the cylinder 34 and caused to act on said piston 35, said piston begins to move until its finally assumes the position shown in said Fig. 3. It should be also appreciated that at no time of the operation of the pump is its 10 discharge equal to exactly zero. During the idling operation, the pump is producing a limited pressure, just suitable to balance the pressure exerted by the spring 38. Should the discharge of the pump accidentally decrease to a point 15 when there is no pressure acting on the piston 35, the pressure of the spring 38 will immediately cause the piston 35 to move toward its retracted position, whereby the discharge of the pump automatically increases until the balanced condition is reestablished.

It will be noted that in certain instances it is necessary to release the oil which may be entrapped in the cylinder 34, in order to permit the movement of the piston 35 into its retracted position. This necessity arises, for instance, when the valve setting is changed from a feeding movement to a rapid return movement. Means for permitting the oil entrapped in the cylinder 34 to escape are exemplified in the present embodiment by the recess 51a, and the waste port 15a. From an examination of Fig. 5 it will become apparent that when the slide member 50 is shifted into the position for rapid return movement of the operating piston, the oil filling the cylinder 34 will escape through the conduit 15, recess 51 and waste port 15a into the storage tank. Also, when the valve setting is changed from idling to rapid advance (see Fig. 4), the oil from the cylinder will escape through the conduit 15, recess 51 and waste port 15a.

It will also be noticed that in all operative settings of the valve 40, the end space thereof adjacent to the recess 51a is inoperative and it communicates with the storage tank through the conduit 16, recess of the piston 39a, and waste port 16a, thus preventing entrapment of oil in said space.

In the modified structure embodying my invention, shown in Figs. 6 to 8, inclusive, the general character of the cycle employed, and the 55 operation of the device is similar to that of the preferred structure. However, in this structure I employ different means for controlling the discharge of the pump, designated generally by the numeral 80. In this structure, the pump body 60 31 houses a concentric pump ring 82 cooperating with the rotor 86 keyed onto the shaft 85, said rotor having a plurality of blades 88 sliding in longitudinal radial slots 87. Operation of the rotor 86 and blades 88 is similar to that of the 65 rotor 26 and blades 28 of the preferred structure. Change of the displacement of the pockets formed by said blades 88 is effected in this structure by changing the amount of eccentricity of the axis of the ring 82 with respect to the axis 70 of the rotor 86. When it is desired to have the pump 80 operate at full capacity, the ring 82 is moved into the position shown in Fig. 6, where the amount of eccentricity is the largest. On the other hand, when it is desired to operate the 75 pump at "no-discharge", the ring 82 is bodily

moved into the position shown in Fig. 8, which is a position of exact concentricity of the ring 82 and the rotor 86. With the ring 82 in such concentric position, there will be no relative eccentricity of the rotor 86 and the ring 82, and the displacement of the pockets formed by the blades 88 remains constant during the rotation of the rotor and in such condition no oil is drawn from the slot 91 or forced into the slot 92. Any intermediate position of the ring 82 produces a 10 condition in which the pump 80 operates at a respective intermediate capacity.

Means are provided in this structure for moving the ring 82 and, consequently, changing the volumetric displacement of the pump 80 automatically by the fluid itself in accordance with the pressure in the circuit. The ring 82 has at its outside cylindrical surface four milled flat portions. Two of them are intended to adapt it for cooperation with the guiding flats 83 and 84 of 20 the pump body 81, while the other two, cut at an angle of 90° to those cooperating with the surfaces 83 and 84, are adapted to bear the pressure of pistons 95 and 96. The piston 95 is adapted to operate in an eccentricity-decreasing 25 cylinder 93 cast integrally with the pump body 81, and the piston 96 is adapted to operate in the eccentricity-restoring cylinder 94 integral with the pump body 81. Piston 95 has a larger diameter than has the piston 96, and therefore 30 with the same pressure in both cylinders, the piston 96 will exert upon the pump ring 82 a much greater force than will the piston 95. The cylinder 94 is connected by means of the conduit 18 with the discharge conduit 12. The piston 96 is 35 aided in its movement toward the rotor 86 by a spring 97, the initial compression of which is regulated with the aid of a screw 98.

For the rapid advance of the piston 61, the control valve is set in position illustrated in Fig. 4. 40 The flow of the oil in this condition is as indicated by arrows, it being pumped into the space 63 of the cylinder 60 and allowed to escape freely from the space 64 through the escape opening 45. In this condition there will be no pressure built in 45 the cylinder 93, while there will be some pressure transmitted from the discharge conduit 12 into the cylinder 94. Aided by the spring 97, the piston 96 is capable in this condition to exert a sufficient force to move the ring 82 all the way 50 toward the piston 95 until it reaches the stop 93a. In this position of the ring 82, the eccentricity 55 will be greater, and the pump will operate at its maximum capacity, effecting a rapid movement of the piston 61. To change the rapid movement 60 of the piston 61 into a slow feeding movement, the control valve is set in the position shown in Fig. 6. In this condition the free escape opening 45 is closed, and the cylinder 93 is communicating 65 with the back-pressure space 64. The free escape of the oil being prevented, the piston 61 ceases to move, and pressure is built up in the space 63, space 64, and in the cylinder 93. Because of the pressure in the cylinder 93, the piston 95 operates to move the ring 82 toward a position of decreased eccentricity, causing the pump 80 to decrease the rate of its discharge. The back-pressure 70 in the space 64 is relieved in this condition only because of the operation of the metering device 70, and it is the rate of this "metering off" 75 action of the device 70 that determines the rate of the feeding movement of the piston 61, while the amount of eccentricity of the ring 82 determines the rate of discharge of the pump 80. In other words, the back-pressure in the space 64

is maintained at such a magnitude as to maintain the proper eccentricity of the ring 82, and to produce with the aid of the piston 95 such a rate of pump discharge as to correspond to the rate of metering action of the device 70. Of course, the pump must be tested and regulated with the aid of the screw 98 to produce in these conditions such a balanced action.

Rapid return movement of the piston 61 is produced when the control valve is set in the position shown in Fig. 5, in which condition no pressure will be applied to the piston 95, and the pump will operate at increased capacity, pumping oil into the space 64, while the oil from the space 15 63 will be allowed to escape through the opening 46 into the storage tank.

For idling operation the valves 39 and 40 are set as illustrated in Fig. 8. In this condition the entire discharge of the pump 80 is directed into the cylinders 93 and 94, but, because of the difference in the respective piston areas, a much greater force is exerted by the piston 95, and it moves the ring 82 into the position of exact eccentricity with the rotor 86, in which condition 25 the pump 80 does not produce any discharge.

The oil which may be entrapped in the cylinder 93 is released by operation of the means described in connection with the preferred structure, and their separate description is dispensed 30 with for the above reasons.

It will be noted that, with the exception of the position for idling operation of the pump, the valve 40 is hydraulically balanced, that is all hydraulic forces applied thereto will balance each 35 other and, consequently, there is no necessity of firmly locking the sliding member 50 in any of the positions. Also, the resistance of said member 50 to manual operation will be limited to the mere friction.

40 Thus in one of its broader aspects my invention contemplates providing a novel hydraulic device for hydraulic feeds and controls, in which the rate of intake and discharge of the pump are changing in accordance with the discharge requirement for a particular type of movement of the hydraulically actuated member, and in which 45 said change of intake and discharge is effected automatically by the pressure of the liquid fluid itself.

50 Although only two embodiments of my invention have been illustrated and described, other changes and modifications in the form and arrangement of parts, which will now appear to those skilled in the art, may be made without departing from the scope of my invention. For instance, other means for changing the eccentricity of the pump than those employed in the herein-described embodiment may be used. Other types of pumps, such as reciprocating pumps of 55 changing stroke, and other types of controlling valve may be employed.

I claim:

1. In a hydraulic device for effecting hydraulic feeds or the like, a pump of variable discharge, 60 an operating cylinder, a piston reciprocable in said cylinder and actuated by the pressure of discharge of said pump, and means operated at a predetermined time by the back pressure created in said cylinder by said piston for changing the rate of discharge of said pump in substantially 65 inverse proportion to the magnitude of said back pressure.

2. In a hydraulic device for effecting hydraulic feeds or the like, a pump of variable discharge, 70 an operating cylinder, a piston reciprocable in

said cylinder and actuated by the pressure of discharge of said pump, and means including a reciprocal spring actuated piston operated at a predetermined time by the back pressure created in said cylinder by said piston for changing the rate of discharge of said pump in substantially inverse proportion to the magnitude of said back pressure. 5

3. In a hydraulic device for effecting hydraulic feeds or the like, a pump of variable discharge, 10 an operating cylinder, a piston reciprocable in said cylinder and actuated by the pressure of discharge of said pump, means operated at a predetermined time by the back pressure created in said cylinder by said piston for changing the 15 rate of discharge of said pump in substantially inverse proportion to the magnitude of said back pressure, valve means adjustable to preclude operation of said means by the back pressure, and means for metering off the fluid at a predetermined rate from the back pressure side of said cylinder. 20

4. In a hydraulic device for effecting hydraulic feeds or the like, a pump of variable discharge, 25 an operating cylinder, a piston reciprocable in said cylinder and actuated by the pressure of discharge of said pump, means operated at a predetermined time by the back pressure created in said cylinder by said piston for changing the rate of discharge of said pump in substantially inverse proportion to the magnitude of said back pressure, valve means adjustable to preclude operation of said means by the back pressure, and rotary means for metering off the fluid at a predetermined rate from the 30 back pressure side of said cylinder. 35

5. In a hydraulic device for effecting hydraulic feeds and controls, a pump of variable discharge, an operating cylinder with a piston, said piston adapted to be actuated by the pressure of discharge of said pump, and a member operated by back pressure created in said cylinder by said piston, said member adapted to change the rate of discharge of said pump in inverse proportion to the magnitude of said back pressure. 45

6. In a hydraulic device for effecting hydraulic feeds and controls, a pump of variable discharge, an operating cylinder having a piston adapted to be actuated by the pressure of discharge of said pump, a discharge-controlling cylinder having 50 a piston adapted to be operated by back pressure created in said operating cylinder by said operating piston and mechanically connected with the discharge-controlling element of said pump, whereby the discharge of said pump decreases in 55 proportion to the increase of said back pressure.

7. In a hydraulic device for effecting hydraulic feeds and controls, a pump of variable discharge, an operating cylinder having a piston adapted to be actuated by the pressure of discharge of 60 said pump, a discharge-controlling cylinder having a piston adapted to be operated by back pressure created in said operating cylinder by said operating piston and mechanically connected with the discharge-controlling element of said pump, whereby the discharge of said pump decreases in 65 proportion to the increase of said back pressure, and means acting in opposition to said discharge-controlling piston and adapted to move the same into the position corresponding to the 70 full capacity of the pump when hydraulic communication between said discharge-controlling cylinder and the back pressure space of the operating cylinder is interrupted.

8. In a hydraulic device for effecting hydraulic 75

feeds and controls, a positive acting pump of variable volumetric displacement, an operating cylinder having a piston adapted to be actuated by the pressure of discharge of said pump, a displacement controlling cylinder having a piston operatively arranged therein and adapted to be operated by back pressure created in said operating cylinder by the movement of said operating piston, said displacement-controlling piston being operatively connected to the displacement-affecting means of said pump, whereby the volumetric displacement of said pump decreases in proportion to the increase of said back pressure, and a spring acting in opposition to said displacement controlling piston and adapted to move the same, when hydraulic communication between said displacement-controlling cylinder and the back pressure space of the operating cylinder is interrupted, into the position effecting a displacement corresponding substantially to that of the full capacity of the pump.

9. In a device for effecting hydraulic feeds and controls, a rotary pump of variable volumetric displacement, an operating cylinder having a piston slidably arranged therein, said piston adapted to be selectively advanced from one end of the cylinder to the other and to be returned to the starting position by the pressure of the fluid discharged by said pump, a displacement-controlling piston operatively arranged in a suitable cylinder and adapted to respond to the back pressure created in said operating cylinder because of the advance movement of said operating piston and to decrease the volumetric displacement of said pump when said back pressure increases, and a spring acting in opposition to said displacement-controlling piston and adapted to move the same into a position effecting a displacement corresponding substantially to that of the full capacity of the pump when a substantially atmospheric pressure is caused to operate upon said displacement-controlling piston.

10. In a device for effecting hydraulic feeds and controls, a rotary pump including a rotor and an eccentricity ring encircling said rotor, said ring adapted to change, as its eccentricity is affected, the volumetric displacement of said pump from zero to displacement corresponding to full capacity of the pump, an operating cylinder having a piston operatively arranged therein, said piston adapted to be selectively advanced from one end of the cylinder to the other end thereof and to be returned to its starting position by the pressure of fluid discharged by said pump, an eccentricity-controlling piston operatively arranged in a suitable cylinder and adapted to respond to the back pressure created in said operating cylinder because of the advance movement of said operating piston and to affect the eccentricity of said eccentricity ring, thereby decreasing the volumetric displacement of said pump as said back pressure increases, and a spring acting in the direction opposite to that of said eccentricity-controlling piston, said spring adapted to affect the eccentricity of said ring and to increase thereby the displacement of said pump as said back pressure decreases, and to effect the displacement corresponding to the full capacity of said pump when said eccentricity-controlling piston is not subjected to said back pressure.

11. A device for effecting hydraulic feeds or the like, comprising a rotary pump of variable volumetric displacement, an operating cylinder having a piston arranged therein and adapted

to be moved into advance position and to be returned to its starting position by the fluid pressure created by said pump, a metering device operated by the rotor of said pump, hydraulically connected to the back pressure side of said cylinder and adapted to meter off the fluid from the back pressure side of said operating cylinder at a predetermined rate.

12. A device for effecting hydraulic feeds or the like, comprising a rotary pump of variable volumetric displacement, an operating cylinder having a piston arranged therein and adapted to be moved into advance position and to be returned to its starting position by the fluid pressure created by said pump, a metering device operated by the rotor of said pump, hydraulically connected to the back pressure side of said cylinder and adapted to meter off the fluid from the back pressure side of said operating cylinder at a predetermined rate, a displacement-controlling piston operatively arranged in a suitable cylinder and adapted to respond to the back pressure created in said operating cylinder because of the advance movement of said operating piston and to effect in said pump a displacement producing a rate of discharge equal to that of the metering off rate of said metering device.

13. A device for effecting hydraulic feeds or the like, comprising a rotary pump of variable volumetric displacement, an operating cylinder having a piston arranged therein and adapted to be moved into advance position and to be returned to its starting position by the fluid pressure created by said pump, a metering device operated by the rotor of said pump, hydraulically connected to the back pressure side of said cylinder and adapted to meter off the fluid from the back pressure side of said operating cylinder at a predetermined rate, a displacement-controlling piston operatively arranged in a suitable cylinder and adapted to respond to the back pressure created in said operating cylinder because of the advance movement of said operating piston and to effect in said pump a displacement producing a rate of discharge equal to that of the metering off rate of said metering device.

14. A device for effecting hydraulic feeds or the like, comprising a rotary pump of variable volumetric displacement, an operating cylinder having a piston arranged therein and adapted to be moved into advance position and to be returned to its starting position by the fluid pressure created by said pump, a rotary metering device operated by the rotor of said pump, said device being hydraulically connected to the back pressure side of said cylinder and adapted to meter off the fluid by centrifugal action from said back pressure side at a predetermined rate.

15. A device for effecting hydraulic feeds or the like, comprising a rotary pump of variable volumetric displacement, an operating cylinder having a piston arranged therein and adapted to be moved into advance position and to be returned to its starting position by the fluid pressure created by said pump, a rotary metering device operated by the rotor of said pump, said device being hydraulically connected to the back pressure side of said cylinder and adapted to meter off the fluid by centrifugal action from said back

pressure side at a predetermined rate, said device being mounted to rotate about an axis coincident with the axis of rotation of the rotor.

16. A structure as defined in claim 14, said 5 metering device having a body provided with passages communicating with the back pressure side of the operating cylinder and with passages communicating with free escape openings, and an end piece fitting into the end of the rotor 10 shaft and forming pockets of adjustable volume, said pockets adapted in operation to register alternatively with said back pressure passages and with said free escape passages, whereby the fluid 15 is metered off from the back pressure side of said operating cylinder at a predetermined adjustable rate.

17. In a device for effecting hydraulic feeds and controls, a rotary pump having a pump body provided with an intake slot and a discharge slot, a concentric rotor with a plurality of blades 20 operatively arranged in said pump body, and an eccentricity ring of constant eccentricity encircling said rotor and adapted to be moved so as to change the position of its eccentricity with

respect to said slots thereby changing the volumetric displacement of said pump, an operating cylinder having a piston adapted to be selectively advanced from one end of the cylinder to the other end thereof and to be returned to its starting position by the pressure of fluid discharged by said pump, an eccentricity-controlling piston operatively arranged in a suitable cylinder and adapted to respond to the back pressure created in said operating cylinder because of the advance movement of said operating piston and to move said eccentricity ring, thereby decreasing the volumetric displacement of said pump as said back pressure increases, and a spring 10 acting in the direction opposite to that of said eccentricity-controlling piston and adapted to move said eccentricity ring and to increase thereby the displacement of said pump as said back pressure decreases, and to effect the displacement corresponding to that of the full capacity of said pump when said eccentricity-controlling piston is not subjected to said back pressure. 15 20

MAX J. CLARK.
